MILTON H. SHOENBERG AND LESTER SCHON, OF SAN FRANCISCO, CALIFORNIA; SAID SCHON ASSIGNOR TO SAID SHOENBERG

FLASHING LAMP

Application filed October 12, 1926. Serial No. 141,058.

This invention relates generally to electrical devices for securing flashing illumination and particularly to those devices which are adapted to be intimately positioned with respect to the lamp to be illuminated.

In electrical signs, signals or other devices intended to attract attention, it has been common to incorporate means for repeatedly varying the current supplied to one or more lights in order to secure a flashing effect. These flashing systems have been more universally used since the invention of circuit interrupting devices in the form of a wafer or button adapted to be removably inserted in a lamp socket or receptacle beneath the base of a lamp or connection plug. (See Shoenberg Patent No. 1,400,914 and Shoenberg and Schon Patent No. 1,602,088). There are certain instances however where such a button is not particularly well adapted. For example, the socket or receptacle may be hanging in an elevated position, in which case it is difficult to keep the button in the socket while inserting the lamp. Since the button occupies a certain amount of space within the socket, a portion of the metallic lamp base will be exposed or the socket may not be deep enough to engage the lamp base after the button is inserted. It is also desirable to be able to market a certain type of advertising lamp with the assurance that it will always be used in a flashing circuit.

It is an object of this invention to construct an electrical lamp and a circuit interrupter as a unit which may be removably inserted in a lamp socket or receptacle.

It is a further object of this invention to incorporate a certain structure within the base of an electric lamp whereby the interrupter will be permanently associated with the lamp.

It is another object of this invention to provide a novel form of mounting for an interrupter element within the base of an electric lamp.

Further objects of this invention will appear from the following description in which we have set forth the preferred embodiment of our invention. It is to be understood that the invention is to be accorded a range of elec-

trical and mechanical equivalents consistent with the state of the prior art.

Referring to the drawings:

Figure 1 is a cross sectional elevational view of a device incorporating the principles of this invention. 55

Fig. 2 is a top plan view of the mounting for the interrupter element.

Fig. 3 is a bottom plan view of the mounting for the interrupter element. 60

Fig. 4 is a cross section taken along the line 4—4 of Fig. 2. 65

Fig. 5 is a cross-section taken on the line 5—5 of Fig. 3.

The invention comprises generally an electric lamp having a metallic sleeve or other type of base adapted to be removably inserted in a lamp socket or receptacle, in combination with an interrupter element positioned within the base. A novel form of mounting is employed for the interrupter element whereby the period of interruption is made uniform and the device is rendered cheap to manufacture and easy to assemble. The form of the invention which has been illustrated comprises a lamp of the type having a transparent or translucent sealed globe or vessel 10 to which is secured a base 11 which may be inserted in a lamp socket or receptacle. Within the sealed vessel 10 there is disposed the usual light filament 12 which is suitably supported as by means of the stem 13. As the particular lamp shown is of the "tip-less" variety there has been shown a depending tube 14 through which the vessel 10 is evacuated during the process of manufacture. The base 11 is preferably made hollow and disposed within the same there is an interrupter element designated generally at 15. 75

The particular form of base 11 which has been shown is constructed with a metallic sleeve 17 formed with a threaded surface, a central insulated contact 18 being mounted upon the end of the sleeve. While a large percentage of the electric lamps now being manufactured are equipped with a base of this type, it is to be understood that the invention may be incorporated with lamps having any kind of base which may be removably inserted in 100

a suitable socket or receptacle. For example, the base may be of the two-prong contact type or it may have a single prong contact with a grounded metallic sleeve. With the type of 5 base illustrated the terminal wires 19 and 20 from the filament 12 are normally connected to the metallic sleeve 17 and to the central contact 18. In this invention however, for 10 electrically associating the interrupter ele- 15 ment 15 with the lamp, this element is connected in series with one of the terminal wires.

The specific construction of the particular 15 interrupter element employed and its as- 20 sociated mounting is shown in detail in Figs. 2 25 to 5 inclusive. Thus there is shown a relatively 30 flat disc or metallic wafer 22 having a re- 35 cess or cut-away portion 23 offset from the 40 center of the same. Arranged to overlie and 45 operate within this disc there is a bi-metallic 50 strip 24 having its one end mounted upon 55 the disc 22 and carrying a movable contact 26 60 at its free end. This movable contact is 65 adapted to cooperate with a relatively stationary 70 contact 27 carried by the metallic strip 75 28-which is provided with a suitable insulat- 80 ing mounting upon the disc 22. Suitable 85 electrical heating means is provided for the 90 bi-metallic strip 24 as for example, a resistance 95 wire 29 which is wound on top of insulation 100 30 provided upon the strip 24. When a shunt 105 type of interrupter element is desired, the 110 resistance 29 is of relatively high value sub- 115 stantially greater than the resistance of fila- 120 ment 12. In this instance one end of the re- 125 sistance wire is connected to the bi-metallic 130 strip 24 and thus to the movable contact 26, 135 while the other end is connected to the rela- 140 tively stationary contact 27. If a series type 145 of element is desired, the resistance wire is 150 connected in series with the contacts 26 and 155 27 and these contacts are normally closed when 160 the device is not in operation, heating of the 165 bi-metallic strip in this case causing the con- 170 tacts to separate and interrupt the current. 175 45 The operation of both the shunt and series 180 type of interrupter elements is well known 185 and need not be described in detail.

To facilitate positioning the mounting for 190 the interrupter element within the base 11, 195 the disc has been provided with a central 200 aperture 32 for receiving the end of the 205 tube 14. Another aperture 33 may also 210 be provided to permit the terminal wire 215 20 to extend down to the disc for connec- 220 tion to the central contact 18 as shown. 225 This terminal wire may be insulated from the 230 disc 22 as by means of an insulating tube 34. 235 The interrupter element is connected in series 240 with the terminal wires 19 and the metallic 245 sleeve. Thus it has been shown as provided 250 with a soldered connection 36 to eyelet 37 255 which is employed for mounting the strip 28, 260 and the disc 22 is connected or grounded to 265 the sleeve 17 by means of conductor 38. It is 270 65 to be noted that the eyelet 37 is insulated from

the disc as is shown particularly in Figs. 1 70 and 5. With this arrangement no short cir- 75 cuiting of the interrupter element will occur if the disc 22 comes in contact with the sleeve. Furthermore, the metallic nature of the disc 80 serves as a heat storage device to stabilize 85 operation of the interrupter element, thus 90 causing the element to operate to maintain a 95 relatively uniform flashing period. In prac- 100 tice the sleeve 17 is sealed to the vessel 10 as 105 indicated at 39 so that the interrupter ele- 110 ment will be protected from moisture or 115 climatic conditions.

In operation the lamp is simply inserted in 120 a lamp socket or receptacle adapted to fit the 125 particular type of lamp base employed. If 130 a shunt type of interrupter element is em- 135 ployed the contacts 26 and 27 are initially 140 open and current flows through the resist- 145 ance wire 29 and filament 12. Because of 150 the relatively high resistance of the wire 29 155 the filament 12 will not be heated to incandes- 160 cence or at least will not burn at full bri- 165 llancy. When the bi-metallic element be- 170 comes heated contact 26 is moved to contact 175 with contact 27, thus shunting out resistance 180 wire 29 and placing the full potential across 185 the filament 12. The resistance wire 29 then 190 cools to again interrupt the current. Since 195 the device is incorporated in the form of a 200 unit it may be readily inserted with one hand 205 in any lamp socket or receptacle regardless 210 of the elevation or the position of the same. 215 When a lamp is manufactured as a particular 220 advertising device, as by etching or placing 225 certain letters or marks upon the surface of 230 the globe or vessel 10, the manufacturer may 235 always be assured that the lamp will be used 240 in a flashing circuit, since it is impossible for 245 the user to remove the interrupter element 250 and incorporate it in a different system.

This case is in part a continuation of our 255 copending application No. 49,976, filed Aug. 13, 1925 and entitled "Circuit interrupter".

We claim:

A device of the class described comprising a 110 lamp globe, a hollow connector base secured 115 to said globe, a sealing tube extending into 120 said base, a current controlling element dis- 125 posed within said base, and a relatively flat 130 member serving as a mounting for said ele- 135 ment, said member having a recess into which 140 said tube extends.

In testimony whereof, we have hereunto set 145 our hands.

MILTON H. SHOENBERG.
LESTER SCHON.
